UNITED STATES PATENT OFFICE.

MONROE M. McILVAIN, OF PUTNAMVILLE, AND JACOB C. GOSE AND HAMILTON FOSTER PICKETT, OF REELSVILLE, ASSIGNS OF ONE-FOURTH TO LYMAN BEECHER SMITH, OF REELSVILLE, INDIANA.

BALLOT-BOX.

SPECIFICATION forming part of Letters Patent No. 425,238, dated April 8, 1890.

Application filed August 10, 1889. Serial No. 320,365. (No model.)

To all whom it may concern:

Be it known that we, MONROE M. McILVAIN, a citizen of the United States, residing at Putnamville, in the county of Putnam, 5 State of Indiana, and JACOB C. GOSE and HAMILTON FOSTER PICKETT, citizens of Reelsville, in the county of Putnam, State of Indiana, have invented certain new and useful Improvements in Ballot-Boxes; and we do 10 hereby declare the following to be a full, clear, and exact description of the invention, such as will enable others skilled in the art to which it appertains to make and use the same.

15 Our invention is designed to provide an efficient safeguard against the fraudulent depositing and counting of ballots by furnishing the ballot-box with a slide normally covering the ballot-deposit opening, said slide 20 being adapted to be moved by the voter so as to uncover the opening at the time of the insertion of his ballot, at the same time actuating a bell or other audible signal and a registering-dial or other visual signal, and the 25 return of the slide to the normal position after the deposit of the ballot being indicated by a second bell or other audible signal, preferably of different tone or volume from the first, so as to be readily distinguishable therefrom, 30 the whole arrangement being such as to enable the voter and the poll-watchers to know with certainty that the ballot has been duly received and recorded and the apparatus restored to its normal position for use by a succeeding voter, and the recording apparatus 35 acting as a check upon the poll clerks and the inspector to prevent the fraudulent insertion of additional ballots after the voting has ceased.

40 In carrying out our invention we have devised the construction illustrated in the accompanying drawings, wherein—

Figure 1 represents in perspective a ballot-box provided with our improvements. Fig. 45 2 represents in plan the mechanical devices for carrying out the invention, and Fig. 3 represents a vertical transverse section on the plane indicated by the line 3 3 of Fig. 2.

Similar numerals of reference indicate similar parts throughout the several views.

Referring to the drawings, 1 indicates a ballot-box of any conventional form, preferably provided with glass sides, as shown.

The mechanism for attaining the objects of our invention is contained within the cover 55 of the ballot-box, which consists of a top piece 2 and bottom piece 3, forming an inclosing-space hinged at one side to the body of the ballot-box and provided at the other side with locking devices, as illustrated in the drawings. Through the top piece 2 and bottom piece 3, constituting the double cover, are made ballot-deposit slots 4 5, registering with each other, the slot 5 being normally closed by means of the slide-lever 6, pivoted at 7, 60 and held in the position indicated in full lines in Fig. 2 by means of a retractile spring 8, connected at its outer end. One end of the lever 6 is provided with an escapement-lever 9, engaging the teeth of a ratchet-wheel 10, 65 said ratchet-wheel being divided in the form of a graduated scale and provided with numerals corresponding in number with the ratchet-teeth, the entire arrangement being similar to that of a clock-escapement. At its 70 opposite end the lever 6 is provided with a pointed projection, which in its path of movement strikes against the end of a pivoted bell-clapper 11, located intermediate of two bells 12 13, which are preferably of different size 75 or tone, so as to give a different audible signal readily distinguishable to the ear. The lever 6 is provided with an actuating-button 14, playing within a slot 15, made in the top piece 2 of the double cover, and the top piece 80 2 is also provided with a slot, through which can be observed the actuation of the registering-dial.

The parts of our invention being constructed and arranged as described, the operation of it is as follows: The mechanism being normally in the position indicated in full lines in Fig. 2, the voter, to deposit his ballot, draws back the button 14 within the limits of the slot 15, thereby causing the slide-lever 90 6 to turn upon its pivot 7 against the retractile force of the spring 8 until the slot 5 is uncovered. During this operation of uncovering the slot the bell-clapper is actuated in such manner as to ring one of the bells, and 95 100

at the same time the registering-dial is actuated so as to make a revolution of a distance corresponding to one ratchet-tooth. The audible signal is heard by the poll-watchers, giving them warning that a ballot is being deposited, and the visual signal indicates that the ballot is registered. After depositing the ballot the voter releases the button 14, and the spring 8 thereupon returns the slide-lever 6 to the normal position, during which return movement it causes the clapper 11 to actuate the other bell, showing that the ballot-deposit opening is again closed and the ballot-box ready to be used by a succeeding voter. By the use of our invention it will be evident that it is impossible to uncover the ballot-deposit slot without attracting the notice of the poll-watchers, and therefore that ballots cannot be surreptitiously inserted by abstracting their attention for a moment. Moreover, the poll-watchers and the voter himself will be careful to note after the deposit of the ballot that the audible signal of closing is given, and if it is not given will see that the mechanism is put in order before a subsequent ballot is taken.

While in the accompanying drawings we have illustrated the construction which appears to us most desirable for the attainment of the specific purposes of invention, we do not limit ourselves to the exact details of structure of the several parts, but intend to include such mechanical equivalents thereof as may fairly fall within the scope of the invention.

Having thus described our invention, what we, claim and desire to secure by Letters Patent, is—

1. A ballot-box provided with a ballot-deposit opening, a slide normally covering said opening, a bell-clapper interposed in the path of movement of said slide, and two bells actuated by said clapper, one on the opening of the slide and the other on its return movement, substantially as described. 40

2. A ballot-box provided with a ballot-deposit opening, a slide normally covering said opening, a bell-clapper interposed in the path of movement of said slide, and two bells of different tones actuated by said clapper, one 50 on the opening of the slide and the other on its return movement, substantially as described.

3. A ballot-box provided with a ballot-deposit opening, a slide normally covering said 55 opening, a bell-clapper interposed in the path of movement of said slide, two bells actuated by said clapper, one on the opening of the slide and the other on its return movement, and a registering-dial actuated by said slide, 60 substantially as described.

4. A ballot-box provided with a double cover having slots 4, 5, pivoted lever 6, hand-pull 14, spring 8, bell-clapper 11, bells 12, 13, escapement-lever 9, and registering-dial 10, 65 substantially as described.

In testimony whereof we affix our signatures in the presence of two witnesses.

MONROE M. McILVAIN.

JACOB C. GOSE.

HAMILTON FOSTER PICKETT.
